UNITED STATES PATENT OFFICE

AXEL ALFRED PETERSON, OF BENSON, MINNESOTA

MANURE LOADER

Application filed August 26, 1930. Serial No. 477,959.

This invention relates to loading devices and particularly to devices for loading manure from a pile of manure on to a wagon. The general object of the invention is to provide a very simple loader of this character which is formed of two sections, one of these sections being formed to provide a trough which is normally supported in an upwardly inclined position and discharges at its upper 10 end into the wagon, the other section being designed to lie upon the pile of manure, both of said sections being provided with sprocket wheels and there being sprocket chains running over the sprocket wheels and carrying 15 forks whereby the manure is scraped away from the pile of manure, drawn into the trough, dragged up the trough and discharged at the upper end of the trough into the wagon.

20 A further object is to provide a mechanism of this character which includes a rocker which supports the trough and which is so formed that the uppermost trough may be rocked upon the rocker to any extent required and that the mechanism may be rotated upon the rocker as upon a vertical axis.

25 A further object in this connection is to provide a driving motor mounted upon the rocker at the center thereof and operatively engaged with the endless chains to drive it.

30 Other objects will appear in the course of the following description.

My invention is illustrated in the accompanying drawings, wherein:—

35 Figure 1 is a side elevation of a manure loader constructed in accordance with my invention;

40 Figure 2 is a section through the trough at the extreme end thereof looking toward the driving pulley;

45 Figure 3 is a section on the line 3—3 of Figure 1;

50 Figure 4 is a fragmentary plan view of the gathering and trough sections;

55 Figure 5 is a fragmentary plan view of the trough section;

60 Figure 6 is a section on the line 6—6 of Figure 4;

65 Figure 7 is a longitudinal sectional view

downward from the forward end of the trough;

70 Figure 8 is a sectional view on the line 8—8 of Figure 4;

75 Figure 9 is a front elevation of the rocker.

80 Referring to these drawings, 10 designates a trough, the detailed construction of which will be hereafter adverted to. This trough is formed of sheet metal, may have any desired length and is supported upon a pair of 85 rockers 11.

85 These rockers may be of channel iron or other suitable material and mounted upon the rockers is a platform 12 adapted to support a motor 13. Extending upward from the 90 ends of the platform are the supporting braces 14 which at their upper ends are connected to the inclined trough 10. Cross braces 15 are disposed between the beams 14 and transversely of these beams. It will be 95 seen from Figure 9 that the beams not only extend upward but inward so that the rocker has a base wider than the width of the trough 10. The upper end of the trough is formed with an opening 16 and the lower end of the 100 trough is opened as at 17 at the end of the trough. Mounted upon the sides of the trough are brackets 18 which support the sprocket wheels 19. The uppermost sprocket wheels 19 are mounted upon a shaft 20 carrying a pulley 21 over which passes a driving band or belt 22 which extends down to the motor 13 so that thus the uppermost sprocket wheels are driven from this motor.

105 Hinged at 23 to the lower end of the trough 10 is a frame 24 consisting of two lateral beams connected by transverse braces, and mounted upon this frame at the ends thereof and if desired, between the ends thereof, are the sprocket wheels 25 carried upon transverse shafts 26 mounted in supporting brackets 27.

110 Engaging with the sprocket wheels 19 and 25 are the endless sprocket chains 28 connected at intervals by the transverse bars 29 having outwardly projecting prongs 30, 115 constituting rakes or forks.

120 At the junction of the frame 24 with the trough 10, the upper flight of the sprocket chains is held down by idle sprocket wheels 31 so that the frame 24 can turn into any 125

desired angular relation to the trough and the upper flight of the carrier formed of the chains 28 will be held down into proper contact with the sprocket wheels below. The 5 tines or forks 30 extend downward below the frame 24 so as to engage the manure on the pile and carry this manure into the lower end of the trough 10, then up the trough 10 and discharge it through the opening 16, the 10 sprocket chains moving in the direction of the arrow in Figure 4.

The detailed construction of the trough 10 is best seen in Figure 2. The rearward end of the trough is extended to form a shoe 32 15 preferably reinforced. The sides of the trough are made of sheet metal braced by the angle irons 33 at the corners of the trough. The brackets 18 are disposed exteriorly to the angle irons 33 and extend above the angle 20 irons to provide bearings 34 for the shafts 35 which carry the sprocket wheels 19.

The operation of this mechanism will be obvious from what has gone before. The rocker 11 permits this device to be adjusted 25 to any desired level and at the same time the device as a whole can be turned around a vertical axis common to the rockers. The frame 24 will adjust itself to the pile of manure. Thus the frame may be raised up 30 to rest at an incline upon the inclined surface of the pile of manure and then as the pile decreases the frame 24 will gradually lower into a horizontal position until all of the manure has been discharged from the 35 pile. The outer end sprockets on the frame 24 may be made adjustable so as to permit the frame 24 to be turned over upon the trough so as to permit the machine to be readily shifted into any desired position and 40 readily moved.

Obviously many minor changes might be made in the details of construction without departing from the spirit of the invention as defined in the appended claims.

45 I claim:—

1. In a manure loader, a trough opening at its lower end and having a discharge opening at its upper end, a rocker supporting and rigidly connected to the trough and disposed 50 intermediate the ends of the trough, the rocker comprising a plurality of laterally spaced arcuate elements rigidly connected to each other, the rocker supporting the trough in an upwardly inclined position, a frame hinged 55 to the lower end of the trough, sprocket wheels mounted upon the trough and frame, an endless element trained over said sprocket wheels and having forks adapted to travel up the trough, and a motor on the rocker operatively 60 connected to certain of the sprocket wheels whereby to drive the endless element.

2. In a manure loader, a trough opening at its lower end and having a discharge opening at its upper end, a rocker supporting the trough and affording means whereby the 65

trough may be rotated around a vertical axis, the rocker comprising a plurality of arcuate elements disposed in parallel relation and rigidly connected to each other, the rocker being rigidly connected to and engaging the trough midway of its length, a frame hinged to the lower end of the trough, sprocket wheels mounted upon the frame and trough, an endless element trained over said sprocket wheels and having forks adapted to travel up the bottom of the trough and over said frame, a driving shaft carrying the uppermost sprocket wheels on the trough, a motor mounted upon the rocker and an operative connection between the motor and the shaft. 70 75

3. A manure loader including a trough of sheet metal, reinforcing angle irons extending the length of the trough at the top and bottom thereof, brackets mounted upon the sides of the trough and extending above the same, a pair of arcuate elements constituting a rocker and supporting a platform, supports extending upward from the platform and rigidly engaged with the trough midway of its length and supporting the trough in an upwardly inclined position, the lower end of the trough having an opening and the bottom of the trough adjacent its upper end having a discharge opening, shafts mounted in said brackets, sprocket wheels mounted upon said shafts, the shaft of the uppermost sprocket wheels carrying a driving pulley, a motor mounted upon the platform and having a driving connection to the driving pulley, a frame hinged 80 85 90 95 100 105 110 115 120 125 130

135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970 975 980 985 990 995 1000

4. A loader of the character described comprising a trough opening at its lower end and having a discharge opening at its upper end, a rocker for supporting the trough, the rocker comprising a plurality of arcuate members rigidly connected to each other, supporting members extending upward from the forward and rear ends of the rocker and rigidly connected thereto and rigidly connected at spaced points to the trough, said rocker supporting the trough in an upwardly inclined position, sprocket wheels mounted upon the trough, an endless element trained over said sprocket wheels, and a motor mounted upon the rocker below the trough and operatively connected to certain of the sprocket wheels whereby to drive the endless element. 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970 975 980 985 990 995 1000

5. In a loader of the character described, a trough open at its lower end and at its upper end, a rocker supporting the trough and disposed intermediate the ends thereof, said rocker including a plurality of arcuate ground engaging elements rigidly connected to each other, the rocker having a width greater than that of the trough, members rigidly engaged 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970 975 980 985 990 995 1000

with the rocker adjacent opposite ends thereof and adjacent opposite ends of the arcuate elements, said members extending upward and inward both longitudinally and laterally and being rigidly engaged with the trough, sprocket wheels mounted on the trough, an endless element trained over said sprocket wheels, and a motor mounted on the rocker and beneath the trough and operatively connected to certain of the sprocket wheels whereby to drive the endless element.

In testimony whereof I hereunto affix my signature.

AXEL ALFRED PETERSON.
